UNITED STATES PATENT OFFICE

165,031

FIREPLACE SCREEN

John B. Turner, Norwich, N. Y.

Application August 23, 1951, Serial No. 16,410

Term of patent 14 years

(Cl. D81—5)

To all whom it may concern:

Be it known that I, John B. Turner, a citizen of the United States, residing at Norwich, in the county of Chenango and State of New York, have invented a new, original and ornamental Design for a Fireplace Screen, of which the following is a specification, reference being had to the accompanying drawing, forming part hereof.

Fig. 1 is a front elevation of a fireplace screen, with the curtains closed, showing my new design;

Fig. 2 is a perspective view of the fireplace screen illustrated in Fig. 1, with the curtains partially drawn apart; and

Fig. 3 is a side elevation of the fireplace screen illustrated in Fig. 1.

I claim:

The ornamental design for a fireplace screen, as shown.

JOHN B. TURNER.
